UNITED STATES PATENT OFFICE.

ALONZO ALDRICH, OF BELOIT, WISCONSIN, ASSIGNOR TO BELOIT IRON WORKS, OF BELOIT, WISCONSIN, A CORPORATION OF WISCONSIN.

SHAKING MECHANISM.

Application filed September 6, 1924. Serial No. 736,271.

This invention relates to improvements in shaking mechanisms and more particularly to the means for varying the amplitude of the vibrations. It is frequently desirable in shaking mechanisms to vary the amplitude of the vibrations, and in mechanisms of this kind which are used in connection with paper making machines it is desirable to vary the amount of the shake so as to obtain the desired interweaving of the fibres for varying grades of paper and varying grades of pulp.

It is therefore an object of this invention to provide a shaking mechanism in which the amplitude of the vibrations may be varied while the machine is in operation.

It is also an object of this invention to provide a shaking mechanism of this class which is adapted to be used in connection with a paper making machine.

It is a further object of this invention to provide an adjustable shaking mechanism for use with a Fourdrinier machine.

It is also an object of this invention to provide a device of this class in which a biased shaft slidably engages a movable block so as to vary the distance between the center of said block and the axis of rotation of the shaft.

Other and further important objects of this invention will be apparent from the disclosures in the specification and the accompanying drawings.

This invention (in a preferred form) is illustrated in the drawings and hereinafter more fully described.

On the drawings:

Figure 1 is a plan view of the shaking mechanism.

Figure 2 is a cross section along line 2-2 of Figure 1.

Figure 3 is a cross section along line 3-3 of Figure 1.

Figure 4 is a side view of the adjustable block removed looking toward the left as the block is shown in Figure 1.

Figure 5 is a side view of the block bearing with the block removed looking toward the right of Figure 1.

Figure 6 is a longitudinal cross section of the shaking mechanism.

Figure 7 shows the shaking mechanism

connected to a paper making machine of the Fourdrinier type.

In the accompanying drawings, which 55 illustrate a preferred embodiment of this invention, and in which similar reference numerals refer to similar features in the different views:

The shaking mechanism as shown in 60 Figure 1 is supported directly above the base 1. Bearings 4 and 5 in line with the bearings 2 and 3 are integral with a bracket 6 rigidly secured to the base structure (see also Fig. 6). A sleeve 7 is rotatably supported in the bearings 2 and 3. Keyed to the sleeve 7 is a large gear 8 which by means of a gear 9 is driven by a motor 10. Integral with the end of the sleeve 7 is a guide 11 a left side view of which is shown in 65 Fig. 5. Upon either side of the guide 11 is a rear guide plate 12 (Fig. 1) secured thereto by bolts fitting into threaded apertures 13 (Fig. 5).

By turning to Fig. 6 is seen slidably 75 mounted on the guide 11 a block or cross-head 14 containing a non-central aperture 15. A connecting rod 16 is strapped to the block 14 which is suitably journalled therefor. Within the sleeve 7 is a shaft 17 one 80 end of which is deflected to slidably engage the aperture 15 of the block 14. Near its other end the shaft 17 is reduced to form a journal 18 and collar 19. The journal 18 is rotatably supported by a bushing 20 rigidly 85 secured in a sleeve 21 by bolts 22 as shown in detail in Fig. 2. The sleeve 21 is longitudinally slidable in the bearing 4 and is apertured and threaded at one end to receive the screw end of an adjusting shaft 23. The 90 shaft 23 is rotatably supported in the bearing 5 and is prevented from longitudinal movement by a collar 24 and an adjusting hand wheel 25 rigidly secured thereto. Mounted on the sleeve 7 is another hand 95 wheel 26 which is secured from rotation thereon by a lock screw 27.

In this embodiment of the invention the connecting rod 16 is pivotally connected at its other end to a horizontally extending arm 100 28 of a bell crank lever. The bell crank lever is pivoted on a shaft 29 and has a vertically extending arm 30. On the upper end of this vertically extending arm 30 is a

shaking post 31 upon which is slidably engaged a cross-head 32. The cross-head 32 may be clamped to prevent slidable movement by means of the clamp 33. Connected to the cross-head 32 by means of a suitable connection 34 is a table roll rail 35. Supporting the rail 35 are springs 36.

The operation is as follows:

The motor 10 transmits a rotary motion to 10 the sleeve 7 by means of the gears 9 and 8 (Fig. 1). Since the block 14 is secured against rotation relative to the sleeve 7 by means of the guide 11 (see Fig. 6), the two members 14 and 17 revolve together. As 15 the block 14 revolves with the sleeve 7, the connecting rod 16 connected to the former is given a reciprocating movement. The amount of this reciprocating movement is dependent upon the amount that the block 20 14 is offset from the center line of the sleeve 7. By rotating the wheel 25 in a clockwise direction the sleeve 21 is drawn to the right in the bearing 4 carrying with it the shaft 17. The shaft 17, by means of its deflected 25 end engaging the non-central aperture of the block 14 causes the latter to move from central position as the former moves to the right thus giving a variable degree of eccentricity to the mechanism which is controlled 30 by the wheel 25.

In the preferred embodiment, the reciprocating motion of the connecting rod 16 is transmitted to the bell crank lever arm 28 (Fig. 7) which through the pivot shaft 28, 35 shaking post 31 and connections thereto to the table roll rails 35 transmits thereto a lateral vibratory movement the amplitude of which is adjustable by the wheel 25 of the shaking mechanism.

40 What I claim as new is:

1. A shaking mechanism in combination with a paper making machine and means comprising a sleeve, a deflected shaft, and a block engaged by said shaft slidable on said 45 sleeve for adjusting the amplitude of the vibrations transmitted to said machine by said shaking mechanism.

2. A shaking mechanism in combination with a paper making machine and means 50 comprising a sleeve a deflected shaft, a block engaged by said shaft and slidable on said sleeve, a second sleeve and a threaded shaft rotatably engaged in said second sleeve for

adjusting the amplitude of the vibrations transmitted to said machine by said shaking 55 mechanism.

3. A shaking mechanism in combination with a paper making machine comprising a connecting rod on said shaking machine, a bell crank lever connected to one end of said 60 rod, a shaking post on said bell crank lever, a table roll rail connected to said shaking post, and springs supporting said rail and means for adjusting the amplitude of the vibrations transmitted to said machine by 65 said shaking mechanism.

4. A shaking mechanism in combination with a paper making machine comprising a connecting rod on said shaking machine, a bell crank lever connected to one end of 70 said rod, a shaking post on said bell crank lever, a table roll rail connected to said shaking post, and springs supporting said rail, and means comprising a sleeve, a deflected shaft, and a block engaged by said 75 shaft slidable on said sleeve for adjusting the amplitude of the vibrations transmitted to said machine by said shaking mechanism.

5. A shaking mechanism in combination with a paper making machine comprising a 80 connecting rod on said shaking machine, a bell crank lever connected to one end of said rod, a shaking post on said bell crank lever, a table roll rail connected to said shaking 85 post, and springs supporting said rail, and means comprising a sleeve a deflected shaft, a block engaged by said shaft and slidable on said sleeve, a second sleeve and a threaded shaft rotatably engaged in said second sleeve 90 for adjusting the amplitude of the vibrations transmitted to said machine by said shaking mechanism.

6. In a paper machine a shaking mechanism comprising a rotatable driving member, a block slidable upon the end of said 95 member, a guide-way on said end for securing said block against rotation relative to said member, and a deflecting shaft extending through said driving member and adapted to engage said block for deflecting 100 said block in said guideway, and means for longitudinally actuating said shaft relative to said driving member.

In testimony whereof I have hereunto subscribed my name.

ALONZO ALDRICH.
